UNITED STATES PATENT OFFICE

EDWARD ERICKSON, OF LYNN, MASSACHUSETTS, ASSIGNOR, BY DIRECT AND MESNE ASSIGNMENTS, TO VICTOR SHOE MACHINERY COMPANY, OF BOSTON, MASSACHUSETTS, A CORPORATION OF MASSACHUSETTS.

LOCK-STITCH SEWING-MACHINE.

1,138,858.

Specification of Letters Patent. Patented May 11, 1915.

Application filed August 18, 1911. Serial No. 644,769.

To all whom it may concern:

Be it known that I, EDWARD ERICKSON, of Lynn, in the county of Essex and State of Massachusetts, have invented certain new and useful Improvements in Lock-Stitch Sewing-Machines, of which the following is a specification.

This invention relates to machines for sewing heavy material such as leather, and refers particularly to that type known as welt sewing machine.

The object of the invention is to provide a machine of this character which shall be simple in construction and operation, and capable of high speed, due to improvements whereby the action of the stitch forming mechanism is obtained direct from the operating power.

To these ends the invention consists in the construction and combination of parts substantially as hereinafter described and claimed.

Of the accompanying drawings,—Figure 1 is a front elevation of the machine complete. Fig. 2 is an elevation from the left of Fig. 1. Fig. 3 is an elevation from the right of Fig. 1. Fig. 4 is a plan view. Fig. 5 represents a section on line 5—5 of Fig. 1, omitting the pitman and some other parts. Fig. 6 represents a section on line 6—6 of Fig. 1. Fig. 7 is an elevation of a portion of the interior of the head of the machine. Fig. 8 represents a detail, partly in section, of the needle carrier and a portion of its actuator. Fig. 9 represents a section on line 9—9 of Fig. 8. Fig. 10 is an elevation of the awl and its carrier. Fig. 11 is a plan view of the same. Fig. 12 represents a detail, partly in section on line 12—12 of Fig. 6. Fig. 13 represents a detail, partly in section on line 13—13 of Fig. 1. Fig. 14 represents a section on line 14—14 of Fig. 13. Figs. 15 and 16 are detail views of the shuttle and its holder. Fig. 17 is a detail side elevation, partly in section, illustrating the operation of parts of the mechanism.

Fig. 18 is a perspective view of some of the mechanism illustrated in Fig. 17, the parts being in the same relative positions as in said Fig. 17. Figs. 19, 20, 21, 22, 23 and 24 are views similar to Fig. 17, but illustrating further steps of the operation of forming a stitch. Figs. 25 and 26 are detail perspective views of parts of the mechanism, illus-

trating further steps of the operation of forming a stitch. Fig. 27 is a detail plan, partly in section, illustrating the operation next following that illustrated in Fig. 26. Fig. 28 is a view similar to Fig. 17, but illustrating the position of the parts when the stitch has been nearly completed and the loop of needle thread has been drawn around the shuttle and just ready to be pulled away from the castor or spreader and tightened upon the work.

The same reference characters indicate the same or similar parts in all of the views.

In the embodiment of the invention illustrated, the base 30 is formed or provided with two uprights or standards 31, 32, having bearings for a lower main or drive shaft 33 and an upper counter shaft 37 and a fixed shaft 38 on the latter of which are mounted certain parts hereinafter described. The main shaft has a pulley 34 for a power driving belt, and has a crank 35 intermediate its ends, to which crank is connected one end of a pitman 36 for actuating the awl and needle as hereinafter described.

The upper portions of the standards are so formed or constructed that the two upper parallel shafts 37, 38 are out of parallelism with the lower main shaft, as best shown by comparing Figs. 1, 2, 3 and 4. The main shaft 33 is provided with a spiral gear 39 indicated by dotted lines in Figs. 1, 2 and 6, which meshes with a spiral gear 40 carried by a vertical shaft 41, the latter having a spiral gear 42 at its upper end meshing with a similar gear 43 carried by one end of shaft 37 so that the latter is driven by the main shaft. The other end of shaft 37 has a larger spiral gear 44 meshing with two pinions 45, 46, rotatably mounted on an arm 47 of standard 31. The pinions 45, 46 are mounted to rotate not in the plane of gear 44 but at an acute angle thereto, for a purpose hereinafter described.

Connected to rotate with the pinions 45, 46, are crank arms 48, 49, having wrist pins 50 on which is mounted the shank 51 of loop spreader 52 which carries the loop of needle thread *a* around the shuttle presently described, as indicated in Fig. 28. The relative sizes of the gear 44 and pinions 45, 46, are three to one so that the loop spreader revolves around the shuttle three times during one rotation of the gear 44. The other

gearing is such that the gear 44 revolves once during the formation of each stitch. The operation of the other members of the stitch forming mechanism, as will become apparent hereinafter, is such that one rotation of the loop spreader 52 is active and the other two idle. As clearly shown in Fig. 2, the construction is such that the loop spreader 52 moves in a circular path the radius of which is substantially the same as the length of the crank arms 48, 49; as hereinafter described, however it engages the needle thread only at a certain point of each third revolution.

15 The shuttle 53 (see Figs. 15 and 16), containing a bobbin 54 for the shuttle thread *b*, has a nose 55 through an aperture or eye 56 of which the thread is led (see Fig. 17). Exterioly a portion of the periphery of the shuttle is formed wedge shaped, the apex 57 of the wedge being substantially at the mid-width of the shuttle, as shown in Fig. 15, this formation facilitating the parting or continued opening of the loop of needle thread after it has been taken by the spreader or caster, and is being drawn around the shuttle thereby. The shuttle holder comprises a box 58 carried by a bracket 59 secured to arm 47 (see Figs. 3, 7 and 15), and a movable cover or retainer comprising an arm 60 (see Figs. 1 and 2), the shank 61 of which is mounted in standard 31 and has a handle 62 adapted to engage a pin 63 removably mounted in said standard. The arm 60 has an upwardly projecting spring lip 64 to lightly bear on the shuttle 53, and a cross arm or plate 65. To remove the shuttle, the pin 63 is moved so that the handle 62 can be operated to rock the shank in its bearing to permit arm 60 to release the shuttle. A reverse of these movements will again confine the shuttle in its box. The front end of plate 65 is turned outwardly somewhat, and opposite, 40 said end, secured to the box 58 (see Figs. 3 and 7) is a lip 66. Said lip 66 and the front end of plate 65, extend outwardly from the shuttle holder sufficiently to insure the loop of needle thread, when carried upwardly by the spreader or caster 52, passing between them and not outside of the holder, the two sides of the loop passing on opposite sides of the shuttle. It will be observed that the shuttle 53 is positioned 45 at an angle to the gear 44, and in order to have the loop spreader 52 properly coöperate therewith so that its operating end will move in the same plane as the front of said shuttle, it is necessary to have the loop spreader operating pinions so positioned 50 that they will rotate in a plane at an acute angle to the gear 44 as heretofore described.

Before proceeding further with the description of the operations on the thread, I 55 will explain the structure of the work feed-

ing devices and the awl and needle mechanism:—The work support comprises an arm 67 (Figs. 1, 2, 3, and 4) having its tip provided with an aperture 68 for the passage of the awl and needle, said aperture being elongated in the direction of the feed because the work is fed by the awl while the latter occupies said aperture. Said arm is adjustably secured to the standard 31, and to this end is formed with an elongated slot 69 through which a screw 70 passes into said standard. The work presser comprises an arm 71 having a foot 72 (Figs. 1, 2, 3, 4 and 6) to bear on the work supported by arm 67, said arm having a hub 73 mounted on a stud 74 supported by standard 32. An arm 75 projecting rearwardly from the hub 73 is provided with a toothed segment 76 which meshes with a pinion 77 fast on rock shaft 78 (see also Fig. 5). Also secured to said shaft 78 is an eccentric 79 forming the fulcrum of the take-up lever 80, having an arm 81 connected by a link 82 with a lever 83 pivoted to standard 31 and carrying a roll 84 engaging a cam groove in disk 85 fixed on shaft 33. This structure provides for varying the operative position of the take-up lever, according to the thickness of the work, because variations in the thickness of the work affect the rotative position of the eccentric 79, through the arm 75, segment 76, pinion 77, and shaft 78. As the eccentric is shifted, it raises or lowers the axis of oscillation of take-up lever 80, thus practically adjusting the fulcrum of said lever. The angle of arm 81 relatively to link 82 is an obtuse one.

In assembling the various parts of the machine it is essential that when the presser foot 71 is in contact with the work support 72 the fulcrum 79 will be so positioned that the initial movement thereof in a counter-clockwise direction when the presser foot is being raised to admit the work will cause but very slight variation either in the operative position of the lever 80 or the throw thereof when actuated by the cam lever 83 through the medium of the connector 82. When, however, the work has been placed upon the support 72 the relative positions of the arm 81 and connector 82 are such that any further counter-clockwise movement of the fulcrum 79 will make the angle of the arm 81 and connector 82 more obtuse and then when the lever 80 is actuated by the lever 83 the throw of said takeup lever 80 will be materially decreased as the presser foot is raised by any increased thickness of work upon the support 72 and a shorter throw will be attained when there is any decrease in the thickness of work. By this means with a uniform movement of the cam lever 83 a varied throw of the takeup lever 80 is assured, which will vary the amount of thread taken up in setting the 105 110 115 120 125 130

stitches formed, it being understood that during the downward movement of the lever 80 the members 170—174 are in position to lock the thread and prevent further movement thereof from the source of supply.

To effect the locking of the presser foot to hold the work tightly during the formation of each stitch, and to release it during the feed of the work, I provide the following mechanism:—Secured to arm 75 is a segment rack 86, meshing with a pinion 87 having a sleeve hub 88 mounted on a crank or wrist pin 89 (see Fig. 12 in connection with Fig. 6) of a stud rock shaft 90 mounted in standard 32 and carrying an arm 91 at its outer end. The arm 91 has a roll 92 engaging a cam groove 93 in a disk 94 secured to shaft 33, said cam groove being indicated by dotted lines in Fig. 6. On the wrist pin 89, at the outer end of sleeve hub 88, is a collar 95 having a ratchet-toothed outer end face 96 engaged by a pin 97 projecting from said wrist pin. A spring 98 is coiled around, and has its ends connected to, the collar and hub so as to constitute a yielding connection between said two members and consequently to cause the presser foot to bear yieldingly on the work with a pressure that may be varied by adjusting the collar rotatively the desired adjustment being maintained by the pin 97 engaging one of the end teeth of the collar. Such yielding pressure however ceases when the awl is penetrating the work. To interrupt this yielding pressure and cause the presser foot to remain immovably in position to resist the force of the upwardly moving awl, I provide means for preventing rotation of the pinion 87 at the proper time. Mounted on the hub 88 are two collars 99 and 100, said collars inclosing a spring 101 which snugly fits the hub and has its two ends connected to the two collars so that relative rotation of the collars will tighten the spring on the hub to act as a clutch brake on the latter, or release it. The collar 99 has an arm 102 provided with a slot which receives a fixed pin 103, whereby said collar is prevented from rotating although it presents no obstruction to the lateral movement of the pinion hub 88 when the wrist pin is shifted. The other collar 100 has an arm 104 connected by a link 105 with a lever 106 fulcrumed on a stud 107 and having a roll 108 engaging a cam groove 109 in disk 94. Pivoted to the lever 106 at 110 is an arm 111 having a roll 112 engaging the outer surface of the rib which forms the outer wall of cam groove 109. The other end of the arm 111 is formed or provided with a yoke 113 which embraces an eccentric 114 (see dotted lines in Fig. 6) which is mounted on stud 107 and has an arm 115 which enters a notch 116 in a vertically movable bar 117 that is adapted to be lifted

manually, as by a suitable treadle, not shown. When the parts are in the position shown in Fig. 6, the two rolls 108, 112, follow the cam rib and cause the lever 106 to be so actuated that the collar 100 is rotated sufficiently to tighten the spring 101, and prevent the presser foot from yielding excepting when the feed is taking place. The gripping effect of the coiled brake spring 101 is obtained regardless of the thickness of the work. That is, when the presser foot is lifted for the introduction of work and then descends upon the work under the pressure of spring 98, it may occupy a higher or lower position according to the work. But the grip to hold it there will be just as effective whether the work be thick or thin.

The hub 73 of the presser foot arm or lever is provided with an arm 118 having a pin 119 which projects across the top of bar 117. When the bar 117 is lifted, as when work is to be introduced, the action on arm 118 is such as to raise the presser foot 72. Before this, however, the arm 115 is actuated so as to rock the eccentric 114 and swing arm 111 to throw the roll 112 outwardly and then as the cam disk 94 rotates, a recess 120 in the inner wall of cam groove 109 comes to a position opposite roll 108 so as to relieve outward pressure on said roll and thus relieve the braking effect of spring 101 and permit the presser foot to be lifted by the further upward movement of bar 117.

Referring to Figs. 8, 9, 10 and 11, in connection with Figs. 1, 2, 3, 4 and 6, the curved needle 121 is secured to a carrier 122 which is oscillated by the pitman 36, said carrier having an arc slot 123, the purpose of which will be presently described. The needle carrier 122 is mounted on the hub 124 of the needle guide or support 125 which latter is mounted to oscillate on the fixed stud 126 which is mounted in fixed bracket arms 127 and 128, and has a flange 129 provided with a pin 130 projecting laterally into a recess 131 formed in one end of the hub 124. The hub 124 is formed with a pocket for a roll 132 the diameter of which is greater than the thickness of said hub, the inner surface of the portion of the needle carrier 125 which is mounted on said hub 124 being formed with a shallow recess so that when the parts are in the position shown in Fig. 8, the roll locks the said hub 124 and needle carrier together to cause the needle guide 120 and needle to oscillate together. The surface of stud shaft 126 is formed with a depression or recess 133 which permits the roll 132 to recede from the needle carrier and unlock it from the hub 124 so that said carrier may oscillate on said hub while the latter remains stationary. This structure provides for a lost motion connection between the needle and needle guide the latter being, however, positively actuated by the 130

needle carrier. The carrier 122 is provided with a pin 134, one end of which extends into an arc-shaped recess 135 in a flanged portion of the hub 124.

- 5 When the parts are in the position shown in Figs. 8 and 9, the needle carrier and the guide are positively locked together because the roll 132 is partly in the pocket of the hub 124 of the guide and partly in the recess 133 in the inner surface of the hub of carrier 122.
- 10 As the needle advances to enter the work the roll rides over the surface of fixed stud 126 and the positive lock continues so that the guide is forced to move also, until the 15 roll 132 reaches the recess 133 and drops thereinto sufficiently to release said roll from the recess in the inner surface of the hub of carrier 122. At this point the upper end of recess 131 reaches the fixed pin 130 and 20 the guide is stopped; but the needle can continue, so as to perform its function, the pin 134 passing idly along the arc recess 135. The roll 132, being partly in the stud recess 133, locks the guide to the stud. On the 25 turn movement, the guide remains locked to the stud until the recess in the hub of the carrier comes opposite the roll, and at the same time the pin 134 reaches the rear end of arc recess 135 so that continued rearward 30 movement toward the position shown in Fig. 8 causes the hub 124 to pull the roll out of inner recess 133 so that the roll is shifted into the outer recess in the hub of the carrier thus again locking the two oscillating 35 members 122, 125 together so that the guide must follow the movements of the needle until the latter is again just about to enter the work. It will thus be seen that the needle guide is intermittently locked positively to oscillate in unison with the needle, when the latter is out of the work, and alternately therewith is positively locked in a stationary position while the needle is in the work.
- 40 The curved awl 137 is secured to a carrier 138, the hub 139 of which is mounted to oscillate on fixed stud 126, said hub having an annular groove 140 and an arm 141 one end of which extends laterally to form a 45 lug 142 which enters the arc slot 123 of the needle carrier, so that as the needle carrier is actuated by the pitman 36, said carrier operates the awl by means of slot 123 and the lug of the awl carrier, although with a 50 lost motion that permits the awl to remain in the work until the needle is just about to enter the work.

After the awl penetrates the work on its upward movement, it is shifted laterally to effect the feed, this lateral movement being a variable one as presently described. The awl carrier hub 139 is so mounted on the shaft 126 that it can be moved longitudinally thereof by means of a yoke 143 (Figs. 65 1 and 6) which engages the annular groove

140 (Fig. 11) said yoke being carried by an arm 144 secured to a slide 145 mounted in standard 32. The slide 145 is pivotally connected at its outer end to the upper end of a lever 146 (see also Figs. 3, 4 and 13) 70 mounted between brackets 147 secured to standard 32. The brackets and the lever are formed with vertical slots in which are mounted three slide blocks 148, 149 and 150 of which the middle one, 149, is the fulcrum block for the lever 146, the other two 75 constituting bearings for a shaft 151 which passes through all three blocks. Practically the shaft 151 constitutes the fulcrum for lever 146, the block 149 serving to take up 80 wear between the shaft and lever. Chiefly to distinguish it from the adjustable bearing blocks or slides 148 and 150, I refer to the slide 149 as the fulcrum block or slide. The lever 146 extends below the brackets 147 and 85 carries a roll 152 which is actuated by a cam groove in a hub 153 secured to main shaft 38.

Adjustment of the length of feed is effected by varying the position of the fulcrum block or slide 149. To this end, one 90 or more pinions 154, 155 are connected to the shaft 151, to be rotated thereby, said pinions meshing with vertical racks 156 supported by standard 32. I prefer to supply two such pinions as illustrated, in order to 95 insure freedom of adjustment of the shaft, but do not limit myself thereto, as the pinion 155 might be omitted. The pinion 154 is not directly secured to the shaft (see Fig. 13), but is connected by screws 157 to a disk 100 158 which has a spline connection with the shaft and is provided with a series of peripheral notches 159 and a series of curved recesses 160. Surrounding the disk 158 is a block 161 having a straight edge bearing 105 against the base of a rack 156 (Figs. 1, 4 and 14) whereby said block may slide vertically but is held from rotating on the disk. Secured to the block is a spring 162 carrying a latch 163 which passes through a slot in 110 the block 161 to engage either one of the notches 159 of disk 158 to prevent it and its connected pinion 154 and shaft 151 from rotating, whereby the fulcrum block 149 is held in its adjusted position. Mounted on 115 the front end of shaft 151 is a sleeve 164 having a handle 165 and a cam flange 166, the latter having a pin 167 entering one of the curved recesses 160. The sleeve is held 120 on the shaft by a nut 168 fitting the threaded end of the shaft. By turning the handle 165 to the left (see Fig. 14) the edge of the cam flange first lifts the latch 163 and then when the pin 167 reaches the end of the recess 160 the disk 158 is rotated so that the engagement of pinion 154 with rack 156 125 will cause the shaft 151 to move upwardly, carrying the blocks 148, 149, 150 with it and resulting in shortening the length of the feed. When the cam flange 166 is moved as 130

just described, it exposes the next notch 159 so that as the disk is then rotated, the latch 163 will drop into that exposed notch thus limiting the adjustment of the feed to an extent prescribed by the distance between two notches. Of course a reverse movement of the handle will result in a lengthening of the feed. Turning the handle to its limit first one way and then the other will enable the feed to be quickly shifted between two prescribed limits. If it be desired to occasionally effect a greater variation of the feed, the operator may insert a finger under the up-turned end of the spring 162 and disengage the latch, then rotate the disk 158 and pinion 154, by means of the handle 165 to the desired extent, and then lock these parts in that adjustment by letting the latch engage a notch 159. Such operation would, of course, carry the cam flange away from coöperative relationship with the latch, but by loosening the nut 168 sufficiently to permit the pin 167 to be disengaged from its recess 160, the sleeve 164 and handle and cam flange can be rotated to carry the cam flange to position to coöperate with the latch, and the pin 167 then engaged with another recess 160 and the nut 168 screwed up again. Then the same variation of the feed between two prescribed limits can be quickly effected, but said limits will be for greater or lesser lengths according to which way the sleeve and cam flange have been adjusted.

The needle thread, on its way to the take-up from a suitable spool or other source of supply not shown, passes through a tension device which I will now describe. Referring particularly to Figs. 4, 5 and 6, a rock shaft 169 having an offset arm 170 is mounted in suitable fixed brackets 171, 172, said arm 170 having two hook-shaped projections or pins 173. Mounted at one end in the bracket 172, and at the other end in the fixed portion of the frame and parallel with the rock shaft 169 is a bar 174 which is preferably cylindrical in form as illustrated. Said bar is fixed, being supported at one end in bracket 172 and at the other end in a portion of the frame, and the bracket 171 is fixedly supported by said bar. A spring 175 (see dotted lines Figs. 2 and 4,) is coiled about the rock shaft 169 and is secured thereto at one end and at the other end engages the bar 174, said spring serving to press the arm 170 against the bar 174. Preferably the portion of the arm 170 which bears against the thread, is flattened as shown in Fig. 5. The needle thread passes from the source of supply between the arm 170 and the bar 174 preferably passing once around the arm 170 and between the two hook pins 173, which latter serve to prevent the thread from slipping off or out of position. The thread next passes under the arm 174, around a pulley 176, under a roll 177

carried by the take-up lever 80 and then over a pulley 178, so that the take-up, when operating as hereinbefore described, forms a bight or loop of thread between the two pulleys 176, 178. The thread then passes to the mechanism presently described. The spring 175 acts with sufficient pressure to cause the tension arm 170 to firmly grip the thread to prevent it from being pulled from the source of supply when the take-up operates and the stitch is being tightened. The rock-shaft 169 has secured thereto an arm 179, the end of which projects into the path of movement of a beveled pin 180, projecting from the vertical shaft 41 (see Figs. 4 and 6). Said shaft rotates in the direction of the arrow in Fig. 4 and when the beveled pin 180 passes the end of arm 179, it acts on the latter to rock the shaft 169 in a direction to release the pressure of the tension arm 170, this occurring when the castor 52 is lengthening the loop to carry it to the position shown in Fig. 28. After the member 52 has pulled out the loop of thread and passed it partly around the shuttle 53 into the position shown in Fig. 28, the thread will be locked again by the member 170 and remain locked while the takeup lever 80 operates to set the stitch. It is obvious, therefore, that the member 52 in pulling out the loop of thread always pulls out enough thread for the formation of the next stitch.

To cause the thread *a* to engage the hook of the needle at the proper time and to be disengaged therefrom, I provide the following mechanism:—Referring particularly to Figs. 5, 7 and 17 to 24 inclusive, the thread *a* passes from pulley 178, through an eye 181 formed in the lower end of a lever 182 pivoted at 183 in a bearing in the lower end of an arm 184 depending from a sleeve 185 mounted on the fixed shaft or rod 38 (Figs. 4 and 7). Another arm 186 of, said sleeve has a roll which is acted upon by a peripheral cam 187 formed on a disk 188 secured to rotate with shaft 37. This structure causes the lever 182 to swing bodily forward and back so that its lower end having the thread eye will travel in the path of the arrow heads *c* in Fig. 18. Said lower end also has a lateral motion in the direction of the arrow heads *d* in said Fig. 18, this motion being effected by a cam rib 189 of disk 188, said rib having its opposite sides engaged by two rolls 190 (Figs. 4 and 7) adjustably carried by the upper arm 191 of lever 182. As indicated in Fig. 7, the rolls 190 are carried by a yoke which embraces the sides of the arm 191, a set screw (indicated by dotted lines in said figure), carried by said yoke and bearing against one side of the arm 191, enabling the yoke and rolls to be adjustably secured to said arm. The lower end of the lever 182 is also formed

with a fork 192 separated from the portion having the eye 181 by a recess 193 so that the thread may bridge said recess as illustrated in Figs. 21 and 22. To carry the 5 thread to that position, I employ a finger 194 which has motions imparted to it in the direction of the arrow heads *e* and *f* in Fig. 17. Said finger forms the tip of an upwardly and laterally curved portion of a 10 lever 195 supported by two links 196, 197 (see Fig. 7) pivoted to standard 31 at 198 and 199 respectively, the pivotal connections of the lever with said links being indicated at 200 and 201. To the link 197, which is 15 shorter than link 196, there is pivoted at 202, a link 203, said pivot 202 being intermediate the pivots 199, 201. The link 203 is actuated by an arm 204 of a rock shaft 205, another arm 206 of said rock shaft having a roll which enters a cam groove 207 in 20 one side of disk 188. Said cam groove is of an irregular formation to actuate the rock shaft and the link 203 so that the latter, owing to its connection with the shorter link 25 197 as shown, will cause the finger 194 to reciprocate in the path *f* (Fig. 17) and to move substantially vertically in the path *e*, the upward movement in path *e* occurring when the lever 182 is in its rearward position 30 as shown in Fig. 21, the finger moving from the position shown in Fig. 20 so as to take the thread *a* and carry it across the recess 193 above the guiding eye 181. By the time the lever 182 has moved to the position 35 shown in Fig. 22, the needle 121 has descended and then the short lateral movement of the tip of lever 182 occurs in the path *d* of Fig. 18 so that the thread is carried into the hook of the needle, after 40 which the needle rises as shown in Fig. 23 and carries a loop of thread up through the work to be taken around the shuttle by the caster 52 as presently described. As the needle moves upwardly, the finger 194 follows it, as indicated by comparing Figs. 23 and 24, holding the loop sufficiently taut to keep the thread in the hook of the needle until the loop has been carried through the work. At the end of the forward movement 45 of the finger it reaches and passes slightly to the outer side of, a fixed curved pin 208 mounted in the end of bracket 127 (see dotted lines Figs. 2 and 4), is coiled loop and push it off from finger 194 to free 50 said loop as shown in Fig. 24. The finger then returns rearwardly and downwardly to the position shown in Figs. 19 and 20, ready for its next operation.

To remove the loop from the needle hook 55 and transfer it to a position where it can be taken by the caster 52 and carried around the shuttle, I provide a transferring finger 209 (Figs. 1, 2, 3 and 7) comprising the lower, laterally off-set portion or arm of a 60 vertical rock shaft 210 mounted in a bearing 65 supported by a bracket or arm 212 of standard 31 (see also Fig. 4). The upper end of the rock shaft 210 is provided with an arm 213 which is connected by a link 214 with one arm 215 of an elbow lever pivoted 70 to the standard 31 at 216 and having another arm 217 provided with a roll entering and actuated by a cam groove 218 in disk 188 (see dotted lines, Fig. 7). The finger 209 simply oscillates in a curved path relatively to the axis of shaft 210, said path being indicated by the arrow heads *g*, Fig. 27. When it so moves, a small hooked projection 219 (Figs. 7, 25, 26 and 27) first enters the loop, this occurring when the needle is substantially in the position shown in Fig. 24, and as the finger continues to swing horizontally, it carries the loop aside as shown by comparing Figs. 26 and 27. At this time, the caster 52, following its rapid circular 85 path, is approaching position to take the loop and quickly lift it away from the hook 219 and the hook of the needle. To prevent any possibility of the loop remaining in the hook of the needle, the extreme end of the 90 finger 209 is formed with two inclined ribs or cams 220 between which is a recess for the point of the needle. The timing of the movements of these parts is such that the cam ribs 220 push the loop of thread out of 95 the needle hook (see Fig. 27) as the hook 219 reaches the position to deflect the loop so that it will be taken by the caster 52.

The path of movement of the caster 52 is 100 always the same, but the loop is deflected or transferred to it by the hook 219 of finger 209 only during one of a plurality of rotations, as has been explained, said caster revolving twice without engaging the thread. During the two idle rotations of the caster, 105 the stitch is tightened, and the awl and needle perform their operations for the next stitch. Although the caster revolves rapidly (three times during each stitch) the take-up 110 operates quickly enough to pull the loop off from the caster 52 just after the latter passes the position shown in Fig. 28. To prevent the loop from slipping too far up on the 115 caster when it is first engaged thereby, said caster is provided with a pin 221; and to prevent the loop from slipping off from the 120 caster while being drawn up or lengthened, said caster is formed with a groove or recess 222 in which the loop lies as shown in Fig. 28 in which figure the direction of rotation 125 of the caster is indicated by an arrow.

In describing the operation of the machine, I will refer, first to Fig. 17 which indicates a stitch as having been already formed, when the awl is in the work and in 130 position for feeding, or just having fed the work along. At this time the caster or loop elongator has released the loop and the latter has been drawn tight and the caster is moving in the direction of the arrow. The 135

lever 182 having the eye 181 which guides the thread is at this time substantially stationary, and the finger is moving downwardly past it to the position shown in Fig. 19. Next the lever 182 retreats to the position shown in Fig. 20, and then moves laterally in the direction of the arrow *c* in Fig. 18 to carry the thread *a* to a position so that as the finger 194 rises in the direction indicated by the arrow in Fig. 21, the thread *a* will be carried across the recess 193, the lever then moving forwardly and the finger 194 rearwardly as shown by comparing Figs. 21 and 22, the awl retreating during this time and the needle descending through the hole just formed by the awl, the hook of the needle coming to position so that when the lever 182 returns laterally in the direction of the arrow *d* in Fig. 18, the thread will be engaged by the needle which then rises to the position shown in Fig. 23 and carries the loop up to the position shown in Fig. 24, the finger 194 moving forwardly and giving up its loop, while retaining sufficient tension thereon to hold the loop in the hook of the needle until said loop is carried through the work. As will be observed, the two instrumentalities, viz., the members 182 and 194, operate upon the thread below the work support 67, the operation of these instrumentalities occurring for the purpose of presenting the thread to the needle when the hook of the latter is below the work and work-support. The two other instrumentalities which coöperate with the thread while the needle is above the work and work support, comprise the caster or loop elongater 52 and the finger 209 which transfers the loop to said caster 52. Shortly after the needle rises to the position shown in Fig. 24, the hook or lug 219 of the finger 209 engages one side of the loop, Fig. 25 showing it as just about ready to so engage the loop. The finger 209 then moves to the position shown in Fig. 27 which is a detail plan view partly in section, one side of the loop being carried aside or deflected to a position to be taken by the rapidly revolving caster 52. Fig. 26 illustrates how one side of the loop is lifted or deflected to position for the tip of the member 52 to enter it. Said caster or elongating member 52, revolving in the direction of the arrows, (Figs. 26 and 28) carries the loop to a point a little beyond the upper portion of the stationary shuttle, after which the take-up lever 80 (Fig. 5) descends to pull the loop off from the member 52 and tightens the stitch, the parts at such time being in the position indicated in Fig. 17, preparing for the formation of the next stitch.

I claim:

1. In a sewing machine, a stitch forming mechanism including a shuttle, a needle, a loop caster movable in a circular path

around the shuttle with its thread engaging recess always facing in the same direction, means for imparting to said caster a plurality of such motions during each operation of the needle, means for deflecting the needle thread into the path of the caster during one of said plurality of motions, and means for tightening the loop after it is released by the caster.

2. In a sewing machine, a stitch forming mechanism, including a shuttle, a needle and a loop caster for taking the loop from the needle and casting it over the shuttle, a gear and means for rotating it, two pinions of smaller size than said gear and meshing with it, crank arms connected with said pinions, the caster having a shank connected with said crank arms, and means for tightening the loop after it is carried over the shuttle by the caster.

3. In a sewing machine, a stitch forming mechanism including a shuttle, a needle, a loop caster having means for rotating it around the shuttle a plurality of times during each operation of the needle, a deflector or transference for delivering the loop from the needle to the caster at a point in one of the rotations of the caster, and means for tightening the loop.

4. In a sewing machine, the combination with a hooked needle, a shuttle and a work plate, of means below the work plate for delivering thread to the hook of the needle and means above the work plate for removing the thread from the hook of the needle and carrying it around the shuttle, the means below the work plate comprising a laterally movable thread guide, a lever having a finger for holding the thread in the hook of the needle as the latter rises through the work, two links of different lengths for supporting said finger lever, and means connected with the shorter of said links at a point between its ends for swinging said link, the means above the work plate comprising a finger for deflecting the loop from the needle and a caster to engage the loop and carry it over the shuttle.

5. In a sewing machine, the combination with a hooked needle and a work plate, of a lever having its end provided with a thread eye, a pivotally mounted arm carrying the fulcrum of said lever, means for oscillating the arm in one plane to cause the end of the lever to swing toward and from the point of the needle, means for oscillating the lever in another plane to cause the said eye to carry the thread into the hook of said needle, a loop-drawing finger movable across the path of movement of the said eye, and means for actuating said finger timed to cause it to hold the loop taut and in the hook of the needle.

6. In a sewing machine, the combination with a hooked needle and a work plate, of

a lever having its end provided with a thread eye, a pivotally mounted arm carrying the fulcrum of said lever, means for oscillating the arm in one plane to cause the 5 end of the lever to swing toward and from the point of the needle, means for oscillating the lever in another plane to cause the said eye to carry the thread into the hook of said needle, said lever having a recess adjacent 10 said eye to admit the point of the needle, a loop-drawing finger movable across the path of said eye to engage the thread and bridge it across said recess and means for actuating said finger timed to cause it to hold the loop 15 taut and in the hook of the needle.

7. In a sewing machine the combination with a hooked needle and a work plate, of a lever having its end provided with a thread eye and a recess above said eye, means for 20 imparting to said lever a motion to cause its end to move laterally and also forward and back, a lever having a finger to engage the thread and carry it across the recess in the end of the first mentioned lever, two links 25 of different lengths for supporting said finger lever, and means connected with the shorter of said links at a point between its ends for swinging said link and imparting to the finger lever both vertical and forward 30 and back motions.

8. In a sewing machine the combination with a hooked needle and a work plate, of a lever having its end provided with a thread eye, means for actuating said lever to im- 35 part to its end both lateral and forward and back motions, a finger movable in a path to deflect the thread relatively to the eye

of said lever, and a cam pin to dislodge the loop from said finger.

9. In a sewing machine the combination 40 with a hooked needle and means for engaging a thread with the hook of the needle below the work, of a shuttle above the work, a caster for taking the loop of thread over the shuttle, and a transfferer for removing the 45 loop of thread from the hook of the needle and engaging it with said caster, said transfferer comprising a rock shaft having a substantially vertical axis and having a lower offset portion provided with means for en- 50 gaging the loop, and means for actuating said rock shaft.

10. In a sewing machine, the combination with a hooked needle and means for engaging a thread with the hook of the needle be- 55 low the work, of a shuttle above the work, a caster for taking the loop of thread over the shuttle, and a transfferer for removing the loop of thread from the hook of the needle and engaging it with said caster, said 60 transfferer comprising a finger, a rock shaft carrying said finger, and means for operating said rock shaft, the said finger having a hook to engage the loop held by the needle and having also an inclined or cam portion 65 to dislodge the loop from the hook of the needle.

In testimony whereof I have affixed my signature, in presence of two witnesses.

EDWARD ERICKSON.
